TOY STORE

Albert E. Beethoven, Brooklyn, N. Y., assignor to Toymaster Products Co., Inc., Passaic, N. J., a corporation of New Jersey

Application February 26, 1953, Serial No. 23,801

Term of patent 14 years

(CL. D34—15)

To all whom it may concern:

Be it known that I, Albert E. Beethoven, a citizen of the United States of America, residing at Brooklyn, in the county of Kings and State of New York, have invented a new, original, and ornamental Design for a Toy Store, of which the following is a specification, reference being had to the accompanying drawing, forming part thereof.

In the drawing:

Fig. 1 is a perspective view of a toy store, showing my new design, and looking from one corner of the store.

Fig. 2 is a like view as viewed from the opposite corner.

Fig. 3 is a section on the line 3—3 of Fig. 2.
Fig. 4 is a section on the line 4—4 of Fig. 2.

I claim:

The ornamental design for a toy store, as shown.

ALBERT E. BEETHOVEN.
